Filed Nov. 13, 1962, Ser. No. 72,447

Term of patent 14 years

(Cl. D13—1)

FIG. 1

FIG. 2

FIG. 3

FIG. 1 is a perspective view of a telephone booth for group use showing my new design;

FIG. 2 is a cross section view of the telephone booth for group use shown in FIG. 1 taken along the line 2-2; and

FIG. 3 is a front elevational view of the telephone booth for group use shown in FIG. 1.

The dominant features of my new design reside in the portions shown in solid lines on the drawing.

I claim:

The ornamental design for a telephone both for group use, as shown and described.
